UNITED STATES PATENT OFFICE.

HENRY F. SHARP, OF SOUTH SAN FRANCISCO, CALIFORNIA.

OIL-BURNER.

1,132,801.

Specification of Letters Patent. Patented Mar. 23, 1915.

Application filed October 28, 1914. Serial No. 868,171.

To all whom it may concern:

Be it known that I, HENRY F. SHARP, a citizen of the United States, residing at South San Francisco, in the county of San Mateo and State of California, have invented certain new and useful Improvements in Oil-Burners, of which the following is a specification.

This invention relates to oil burners and 10 more particularly to that class of oil burners adapted to use crude oil distillate and has for its primary object the provision of a burner of the character set forth which shall, be economical, easy to manufacture and in- 15 stall and efficient in operation.

A further object of this invention is to provide a burner of the character described, which shall be adapted to be inserted in the ordinary coal range and used in lieu of the 20 solid fuel therein.

A still further object is to provide a burner for petroleum distillates adapted to generate its own gas at all times to maintain level and even temperature in the heating 25 device in which it is installed.

With the foregoing and other objects in view as will hereinafter appear, this invention consists in the novel arrangement and peculiar combination of the various parts of 30 a crude oil burner as hereinafter described and more particularly set forth in the appended claims.

Referring to the drawings forming a portion 35 of this specification and in which similar reference characters indicate similar parts wherever used: Figure 1 is a top plan view of a kitchen range with the top of the fire box broken away and showing the improved burner installed therein; Fig. 2 is a

40 top plan view of the improved burner; Fig. 3 is a detail perspective of one of the burner tips; Fig. 4 is a detail perspective of the starting pan and baffle plate.

The numeral 5 designates a range of any 45 usual type provided with the usual fire box 6.

While I have shown the invention as applied to a kitchen range, it is to be understood that the burner may be utilized wherever heat is desired. Within the fire box 6 50 is placed a pan 7 having sides 8 and an elongated side extension 9. The pan is so placed in the fire box that the extension 9 is at the back thereof and abuts against the fire brick 10.

55 The burner proper consists of a pipe 11 provided with a valve 12 and in communica-

tion with any source of supply of crude oil distillate which pipe 11 is secured by means of a collar 13 to an expansion chamber 14 of relatively larger diameter than the pipe 60 11 and formed with two expansion rings 15 and 16. A reducer 17 is placed on one end of the expansion chamber 14 and to the reducer is fastened by means of a collar 18 a small section of pipe 19 of the same relative 65 diameter as the pipe 11. A four-way coupling 20 is fastened to the pipe 19 by means of a collar 21 and carries on its laterally extending arms by means of collars 22 and 23 short sections of pipes 24 and 25 and upon 70 its straight way branch is a collar 26 to which is secured a short section of pipe 27 carrying a T member 28 secured thereto by means of a collar 29. By means of collars 30 and 31 secured to the pipes 24 and 25 respectively are supported right angled burner tips 32, 33 having fish tailed tips 34 and 35. The T member 28 carries a collar 36 to which is secured a short section of pipe 37 having a 75 collar 38 carrying an L 39 to which is secured by means of a collar 40 a short section of pipe 41 closed by means of a cap 42. The T member 28 also carries a collar 43 to which is secured a short piece of pipe 44 supporting by means of a collar 45 an L 46 80 85 which in turn supports by means of a collar 47 a pipe 48 closed by means of a cap 49. The burner is installed in the fire box or any other desired location at a point above the pan 7 in such a manner that the fish tailed 90 burners 34 and 35 face the member 9 formed on the pan 7.

The operation of the device is as follows: When it is desired to start a fire in the stove or other heating device, the valve 12 is operated to allow a flow of the oil through pipe 11 from whence it will flow into the expansion chamber 14 and into the closed pipes 41 and 48 and out through the burner tips 34 and 35 as will readily be seen. When 100 a sufficient amount of oil has dripped from the burner tips 34 and 35 into the pan 7, the oil in the pan 7 is then ignited which will cause a flame to strike upwardly against the various parts of the burner and 105 most intensely against that part of the burner composed of the pipes 27, the T 28, and the closed pipes 41 and 48 heating the oil therein to a cracking temperature whereupon gas will be formed within the pipes 110 mentioned and will flow out of the burner tips 34 and 35, causing a V-shaped flame

as shown in Fig. 3 which will strike against the baffle plate 9 and be deflected in the direction of the arrows shown in Fig. 1 through the usual flame chamber around the oven of the stove and out of the stack 50 of the stove.

I realize that considerable variation of the details of my invention may be resorted to without departing from the spirit there-
of and it is not my intention to limit myself to the specific details herein shown and described but to construe the following claims as broadly as the state of the prior art will permit.

15 What I claim is:

1. In an oil burner, the combination with a supply pipe having a controlling valve, of an expansion chamber at one end of said supply pipe, a plurality of closed gas forming members communicating with said expansion chamber, and a plurality of gas burner nozzles positioned intermediate said chamber and gas forming members adapted to direct their flames against said gas forming members and receive a supply of gas from both of said gas forming members and expansion chamber.

2. In a heater, in combination, a drip pan, a baffle positioned thereabove, and a substantially horizontally disposed oil burner positioned above said drip pan com-

prising an expansion chamber provided with a supply pipe, gas forming members communicating therewith, and a plurality of burner nozzles interposed between the expansion chamber and gas forming members adapted to direct the flames past said gas forming members against the baffle from which they are deflected toward said expansion chamber.

3. In a heater, in combination, a vertically disposed baffle, an expansion chamber, a source of supply of liquid fuel communicating therewith at one point and a plurality of gas forming members at another point lying in substantially the same horizontal plane, and a plurality of burners connected intermediate the gas forming members and expansion chamber adapted to receive a supply of gas from both of said gas forming members and expansion chamber, the burners being so positioned as to direct their flames past said gas forming members to the baffle from which point they are deflected backwardly into contact with said expansion chamber and gas forming members.

In testimony whereof I affix my signature in presence of two witnesses.

HENRY F. SHARP.
